Primary Examiner — Dominic Simone*(74) Attorney, Agent, or Firm* — Carol N. Green, Esq.(57) **CLAIM**

The ornamental design for a basketball rivet apparatus, as shown and described.

DESCRIPTION

FIG. 1 is a top perspective view of the basketball rivet apparatus.

FIG. 2 is a bottom perspective view of the basketball rivet apparatus.

FIG. 3 is a top plan view of the basketball rivet apparatus.

FIG. 4 is a bottom plan view of the basketball rivet apparatus.

FIG. 5 is a right side view of the basketball rivet apparatus.

FIG. 6 is a front view of the basketball rivet apparatus.

FIG. 7 is a rear view of the basketball rivet apparatus; and,

FIG. 8 is a front view of the basketball rivet apparatus as attached to a shoe.

The broken lines in FIG. 8 showing the shoe are included for purposes of illustrating environment and form no part of the claimed design.
